UNITED STATES PATENT OFFICE.

JOHN A. LETHERT, OF ST. PAUL, MINNESOTA.

PRICE-INDICATOR.

1,255,897.

Specification of Letters Patent. Patented Feb. 12, 1918.

Application filed May 14, 1915. Serial No. 28,078.

To all whom it may concern:

Be it known that I, JOHN A. LETHERT, a citizen of the United States, residing at St. Paul, in the county of Ramsey and State of Minnesota, have invented a new and useful Improvement in Price-Indicators, of which the following is a specification.

My invention relates to an improvement in price indicators by which two concave 10 pieces of metal shell of similar shape covered on their convex side with paper upon which is printed any desirable numerical monetary figure indicating the price of an article singly or in quantity, and which paper is 15 covered with transparent celluloid, curved slightly inward over the edge of the metal shells, are firmly clasped over each other, one of said metal shells being just sufficiently larger to clasp firmly over the other 20 in such a manner as to securely hold the smaller of the said metal shells in the larger, and thus clearly and evenly exposing the said numerical monetary figure, through the celluloid covering, to the naked eye. The 25 combination is attachable to or placed in close proximity to articles of merchandise or any other salable article by means of a pointed metal stick pin with or without loop or base adjuster, a hook, or other attachable 30 article protruding from the aforesaid combination and attached thereto through the center of said combination by means of a slot into which the head of said pin or hook is soldered and anchored in a metal brace 35 containing said slot, in the center of the concave side of the metal combination. The whole interior of said combination is covered by a filler of corrugated paper for the purpose of making the combination pliable 40 without denting it. The price indicator as described may also, without said pin or hook, be set upon an easel or any other base suited to holding in place the combination.

The object of my improvement is to provide 45 the merchants with a more sanitary, more attractive, more durable and more economical price indicator for their salable articles.

I attain this object by the combination 50 illustrated in the accompanying drawings in which—

Figure 1 is a cross section, from side to side of celluloid covered base for display of the numerical monetary figure, with stick 55 pin and loop or base adjuster attached; Fig. 2 is a section of the celluloid covered base

from front to back, showing clasping of two metal shells, celluloid coating corrugated paper filler, and metal brace in center with stick pin and loop or base adjuster attached; 60 Fig. 3 shows price indicator assembled with hook attached; Fig. 4 shows price indicator assembled with plain metal stick pin attached; Fig. 5 shows price indicator assembled with easel attachment; Fig. 6 shows 65 plan of attachment of price indicator to easel, downward.

Similar letters refer to similar parts throughout the several views.

The concave pieces of metal shell *a* are 70 covered with the paper *g* upon which is printed the numerical monetary figure, which paper *g* is held attached to and against the pieces of metal shell *a* by the transparent celluloid coating *b*, curved 75 slightly inward over the edges of the metal shells *a*, and the combination clasped securely together over the corrugated paper filler *c* within which is confined, in the center of the combination and extending from 80 one end thereof to the other in the concave side of the combination the metal brace or anchor *d*, edged to fit snugly against, and at equal distances from the top and bottom of, the inner walls of the pieces of metal 85 shell *a*, containing at the top or bottom of its center, the slot *e* into which is immovably soldered the head of the metal stick pin *f* or hook *g* extending through the center of the combination through a snugly fitting 90 opening from which it protrudes for the purposes of attachment to salable articles, to which in case the stick pin is used, it is adjusted in a sanitary and ornamental manner by means of loop or base adjuster *h*. 95

For the purposes of firmer attachment to salable articles, or for greater ornamental effect, the combination may also have two slots *e* and two plain or adjustable metal stick pins *f*, fastened and extending in the 100 manner herein described at practical distances from each other and from the center of the combination outward.

The whole combination may be attached in like manner to pillar *j* of base of easel *k*, 105 which pillar *j* may be bent so as to bring the face of the combination directly over the center of the base *k*.

This invention differs from other price indicators in that it is usable for the same 110 purpose in the front and in the back thereof, having both sides of the metal shell

covered with transparent celluloid, and doubling the practicability of said invention; that the pin, hook, easel or other attachment is more firmly fastened in that it is soldered firmly upon a strip of metal fitting tightly within the two shells, and by reason of the soldered part of said pin being within the two shells, is therefore more attractive and less likely to become dislocated.

19 I claim:

1. A price indicating device comprising: a pair of display members having rearwardly turned edges, one of said members being fitted closely within the rearwardly turned edge of the other member to form an inconspicuous joint between said members, and cushioning means interposed between said members to yieldingly resist movement of said members toward each other.
- 20 2. A price indicating device comprising: a pair of display members formed of sheet material and having rearwardly turned edges, said members being joined with their rear surfaces toward each other and with 25 one of said members fitted closely within

the rearwardly turned edge of the other member, resilient cushioning means interposed between said members to yieldingly resist inward movement of said members, and means for supporting the device in any 30 desired position.

3. A price indicating device comprising: a pair of display members formed of sheet material and having rearwardly turned edges, said members being joined with their 35 rear surfaces toward each other and with one of said members fitted closely within the rearwardly turned edge of the other member, a pin mounted between said members and projecting radially therefrom, a 40 plate attached to said pin and extending transversely thereto and engaging the rearwardly turned edge of one of said members to hold said pin in its radially extending 45 position, and cushioning means between said plate and said display members.

JOHN A. LETHERT.

Witnesses:

HENRY B. LEWIS,

ANNA MICKO.
